UNITED STATES PATENT OFFICE

ALBERT G. THOMAS, OF LYNCHBURG, VIRGINIA

DESIGN FOR A PACK OF PLAYING CARDS

Application filed July 5, 1932. Serial No. 44,257. Term of patent 7 years.

To all whom it may concern:

Be it known that I, ALBERT G. THOMAS, a resident of the city of Lynchburg, county of Campbell, and State of Virginia, and a citizen of the United States, have invented a certain new, original, and ornamental Design for a Pack of Playing Cards, of which the following is a specification, reference being had to the accompanying drawing, forming a part thereof.

Figures 1, 2, 3 and 4, are, respectively, face views of certain cards of a pack, the same general scheme of ornamentation, or theme, running throughout them all, showing my new design.

I claim:

The ornamental design for a pack of playing cards as shown and described.

In testimony whereof, I hereunto affix my signature.

ALBERT G. THOMAS.
